ENGINE CONTROL.

1,006,751.

Specification of Letters Patent. Patented Oct. 24, 1911.

Application filed December 2, 1909. Serial No. 530,897.

To all whom it may concern:

Be it known that I, HARRY HERTZBERG and MAURICE J. WOHL, citizens of the United States, and residents of the city of New York, county of Kings, and State of New York, have invented certain new and useful Improvements in Engine Control, of which the following is a specification.

This invention relates to engine governing mechanism, particularly to means for governing internal combustion engines, though the invention may be applied to other types of engine.

The object of the improvements is to render the governing positive and efficient.

Generally speaking, the invention consists in the combination of a variable valve, changes in the degree of opening of which vary the speed of the engine, as, for example, the intake valve of a reciprocating internal combustion engine, a reversible electric motor for increasing and diminishing the degree of opening of this valve, and a centrifugal governor controlling the reversing of the motor.

One of the possible embodiments of the invention is disclosed in the accompanying drawings, wherein:

Figure 1 is a semi-diagrammatic view, showing a reciprocating internal combustion engine in elevation and partly in section, and the centrifugal governor and switch in plan; Fig. 2 is a plan view of the centrifugal governor, switch, and stationary contacts.

Referring now to these views, the numeral 1 indicates an internal combustion engine of the reciprocating kind, 2 a dynamo driven by the engine, and 3 a motor driven by the dynamo. The intake valve is indicated by the numeral 4; this valve being opened by a cam 5, through a push-rod 6 and a rocker 7. The degree of opening of the valve is regulated by the motor 3, through worm gearing 8, which turns an eccentrically journaled pivot 9, on which latter the rocker 7 is supported. It will be understood that, when the motor runs in one direction, the pivot 9 is turned so as to be lowered, whereby greater opening of the valve results, but when the motor runs in the opposite direction, the pivot 9 is turned oppositely, so as to be raised, whereby a lessened opening of the valve is obtained. This particular con-

struction is not new with the present application.

The motor 3 is reversible. In the drawing, the armature is capable of being reversed, 10 being the shunt field; but this arrangement is naturally not imperative.

The numerals 11, 12 indicate the leads from the dynamo to the armature of the motor, the same terminating at stationary contacts 13 and 14. An opposed pair of stationary contacts 15 and 16 is connected with the other pair, 15 with 13 and 16 with 14, whereby opposite stationary contacts are of reverse polarity. The switch 17 carries contacts 18 and 19, suitably insulated, which are connected by wires 20, 21 with the motor brushes. The switch contacts are adapted to rest against either pair of stationary contacts, or, in mid-position, to touch neither pair of stationary contacts. A spring 22 tends to hold the switch 17 with its contacts against contacts 13 and 14, with which arrangement the motor 3 runs to produce maximum opening of the valve 4. Obviously, however, any other suitable means may be employed to tend to throw the switch in one direction, as the weight of the switch itself. The switch 17 is thrown in the opposite direction by a novel form of centrifugal governor 23, the same comprising a ring 24, encircling and spaced from a shaft 25 driven from the engine; the said ring being pivoted to the shaft at 26. The ring 24 is connected with a slidable collar 27 by means of a pivotal link 28; and the collar throws an intermediately pivoted lever 29. A spring 30 connected to lever 29 serves to tend to cause the ring 24 to assume and maintain a position diagonal to the shaft 25; and the tension of the spring may be varied by an adjusting device such as 31. When the rotation of the shaft 25 has caused the ring 24 to assume a position more nearly perpendicular to the shaft, the lever 29 bears against the switch lever 17, and throws the same, first to neutral, and then against the contacts 15 and 16. The contact of the lever 29 against the lever 17 may be timed by a suitable adjusting device, as 32.

Resilient cushioning means are provided in connection with the electrical contacts. Preferably they are associated with the sra-

tionary contacts 13 and 14, and 15 and 16. These contacts are shown as mounted slidably in supporting bars 33, with springs 34 interposed between them and said bars. 5 Suitable adjustable devices, as nuts 35 on the stems of said contacts, limit the extent to which the contacts may be protruded under the influence of the springs.

What is claimed as new is:

- 10 1. A valve controlling mechanism for reciprocating engine valves, comprising in combination, an engine, an engine valve, eccentrically mounted means for actuating said valve, a segmental rack on the axis of 15 said eccentrically mounted means, a motor for varying the position of said eccentrically mounted means, a worm actuated by said motor and meshing with said rack, the action being such that forward movement of 20 the motor swings said eccentrically mounted means to increase the stroke of the valve and reverse movement of the motor swings said means to shorten the stroke of the valve, oppositely disposed contacts, a switch- 25 bar adapted to oscillate between said contacts, means governed by the speed of the engine for oscillating the switch-bar from one set of contacts to the other to reverse said motor, and means for adjusting the 30 periods of contact between said switch-bar

and said speed governed means to vary the limits of speeds at which the stroke of the valve will be changed.

2. A valve controlling mechanism for reciprocating engine valves, comprising in 35 combination, an engine, an engine valve, means for actuating said valve, an eccentric support for said valve actuating means, a segmental rack rotatable on the axis of said eccentric support, a motor for varying the 40 position of said valve actuating mechanism for regulating the stroke of the valve, a worm actuated by said motor and meshing with said rack, a switch for controlling the direction of said motor, means governed by the speed of the engine for actuating said switch to reverse said motor, and means mounted to adjust the periods of contact between said speed governed means and said switch to vary the limits of speeds at which 45 the stroke of the valve will be changed. 5

Signed at Brooklyn, N. Y. city, in the county of Kings and State of New York, this 12th day of November, 1909.
